UNITED STATES PATENT OFFICE.

CHARLES M. STEWART, OF DENVER, COLORADO.

SAFETY-FIRST REMINDER.

Application filed March 2, 1921. Serial No. 449,210.

To all whom it may concern:

Be it known that I, CHARLES M. STEWART, a citizen of the United States, residing at Denver, in the county of Denver and State of Colorado, have invented certain new and useful Improvements in a Safety-First Reminder; and I do hereby declare the following to be a full, clear, and exact description of the invention, such as will enable others skilled in the art to which it appertains to make and use the same.

The object of the invention is to provide a simple and relatively inexpensive but convenient device to serve as a means of reminding and keeping before motormen, engineers and others operating cars and trains on single track and other railroads, the points, on a given schedule on which the train or car operated by such a one is running, at which his train or car should meet and pass trains or cars moving in the opposite direction, with the purpose of avoiding misinterpretation or disregard of orders, and overlooking or forgetting to make and occupy sidings at the proper points and times to give the right-of-way to other cars and trains; and with this object in view the invention consists in a construction, combination and relation of parts of which a preferred embodiment is shown in the drawing, wherein:

Figure 1 is a perspective view of a device embodying the invention, the same being in open or operative position.

Figure 2 is a transverse sectional view of the same.

Figure 3 is a view of the device in the folded condition for transportation.

Figure 4 is a detail view illustrating the arms and manner in which they are secured in place.

The device consists of a casing having the sections 10 and 11, foldably connected as by means of hinges 12, containing respectively the temporary binder clips or split rings 13 and 14 for engagement with schedule sheets or cards 15 and 16, the former representing, for example, the schedule upon which the train operated by a given motorman or engineer is running and the other representing the schedule upon which a train running on the same road or a track in the opposite direction is operating, and indicating by the time designations thereon the points, by comparison with the running

schedule 15, at which the trains should meet and pass each other. Obviously a number of schedules 16 indicating the trains moving in the opposite direction may be used on a single trip in accordance with the schedule 60 15 upon which the train conducted by the operator is running, the trains in the opposite direction being scheduled to leave the starting points at different times and therefore meeting the train traveling upon the 65 schedule 15 at different points in the route of the latter, and for this reason a number of the schedule cards 16 are engaged with the temporary binding means for successive exposure for the guidance of the engineer or 70 motorman. For example when a train operating on the schedule 15 leaves the terminal, the schedule 16 of the train which will first be met thereby should be exposed for the guidance of the engineer or motor- 75 man, and after said train has been met and passed, the schedule 16 should be turned or reversed to the opposite side of the binder clips to expose the next schedule card re- 80 lating to the train moving in the opposite direction which is next to be met and passed, and after the second train has been passed the schedule thereof should be re- 85 versed to expose the schedule of the next train to be met, and so on, the schedule of 85 the train upon which the operator is running being constantly exposed and before him for comparison successively with the schedules of trains moving in the opposite direction, so as to serve as a continuous 90 guide to prevent overlooking an intersection, and making proper provision there- 95 for.

In the construction illustrated a holding device 17 consisting of a pivoted loop is 95 arranged in each section to bear upon and hold in proper position the schedules which are exposed, it being obvious that in reversing the schedule 16 after the train to which it relates has been met and passed, 100 the retaining loop may be swung upward and then replaced to prevent drafts disturbing the schedules and interfering with the proper reading and comparison thereof.

Moreover in order to facilitate the grasping of the edges of the schedule cards or sheets in order to turn the same there is preferably arranged in each section of the casing a lifting device consisting of arms 18, pivoted as at 19 to the bottom wall of the 110

section and extending to the side walls where they are provided with upstanding extensions 20 terminating in finger holds 21 located at or about the plane of the edges of the side walls. It is only necessary to grasp a finger hold and raise the arm in order to expose the edges of the schedules which are lifted thereby to facilitate the turning over of the cards which after raising the retaining loops are repressed thereby and held in proper position for inspection.

It will be understood that the device may be suspended as by means of a ring 22 or the equivalent thereof within convenient view of the engineer or motorman or may be arranged in an open position on a suitable support in front of him or wherever may be most convenient to afford a view of the schedules at all times for guidance as above indicated.

Having thus described the invention, what I claim is:—

A device for the purpose described having a casing consisting of relatively movable sections provided interiorly respectively adjacent their longitudinal centers with temporary binding clips, leaves reversibly disposed on said slips, and lifting means in connection with each section and consisting of arms pivotally connected with the bottom of the section and extending to the side walls thereof beneath the schedules, said arms being provided with terminal upstanding extensions having finger holds.

In testimony whereof I affix my signature in presence of two witnesses.

CHARLES M. STEWART.
